WINDOW FRAME CONSTRUCTION

Wayne A. Norman, Dubuque, Iowa, assignor to Carr, Adams & Collier Company, a corporation of Iowa

Application March 1, 1956, Serial No. 568,825

2 Claims. (Cl. 20—11)

This invention relates to a window frame construction and more particularly to a construction of the window sill.

In the conventional construction of a double-hung window frame or other window frames of the same general type, the brick mold rests on a projection of the sill called a sill. It has not been practical to make multiple window units by placing single window units together because the sill lug which projected beyond the back of the window jambs had to be cut off. This cutting removed the greater part of the sill which, because of its being an end grain, is most effectively treated with toxic preservative treatment. An alternative to this has been to make multiple window units using a long one-piece continuous window sill running under the combined window frame units. The use of the long one-piece window sills is objectionable because they have a greater tendency to twist and warp than do short window sills and in addition create a stocking problem for the dealer.

An object of this invention is to provide a new and improved window frame construction wherein an outer section of the sill has extensions which are of a length so as to terminate flush with the back of the jambs and a brick mold associated with each side jamb of the window has a stepped lower end so that a part thereof rests on the associated sill extension and another part encloses the end of the extension and fills the sill out to full width.

Another object of the invention is to provide a window frame construction comprising spaced apart side jambs, a window sill having a window underlying section extending between the jambs, an outer section of the sill integral with the first section and having extensions beyond the ends of said first section so as to terminate flush with the back of the jambs, a blind stop associated with each jamb, and having its lower end seated on one of said extensions, a brick mold associated with each blind stop having a stepped lower end so that a part thereof rests on the associated sill extension and another part encloses the end of the extension and fills the sill out to full width.

A further object of this invention is to provide a preformed window sill construction for optional use, without cutting, in either a single window unit or in a multiple window unit each of which has spaced apart side jambs wherein the window sill does not require any cutting on the job and adjacent side jambs in a multiple window unit may be positioned in back to back contact.

Another object of the invention is to provide a preformed window sill for use in either a single window construction or in a multiple window unit without any cutting of the sill wherein the window sill comprises a first window underlying section adapted to extend between a pair of spaced apart side jambs and an integral outer section having extensions beyond the ends of said first section of a length sufficient to terminate flush with the back of said side jambs, whereby the sill may be

2

used in a single window construction or may be placed end to end with at least one other sill in a multiple window unit and with adjacent side jambs in back to back contact.

5 The objects of the invention generally set forth, together with other ancillary advantages, are attained by the construction and arrangement shown by way of illustration in the accompanying drawing, in which:

Fig. 1 is a fragmentary view in elevation of a single window construction embodying the invention;

Fig. 2 is a fragmentary front elevation of the construction shown in Fig. 1 and more particularly the lower left corner thereof on an enlarged scale with the window sash and building wall removed;

Fig. 3 is a perspective view of the window construction shown in Fig. 2;

Fig. 4 is a horizontal section taken along the line 4—4 in Fig. 2;

Fig. 5 is a fragmentary view in front elevation of a multiple window unit with the window sash removed; and

Fig. 6 is a horizontal section taken along the line 6—6 in Fig. 5.

While this invention is susceptible of embodiment in many different forms, there is shown in the drawing and 25 will herein be described in detail an illustrative embodiment of the invention with the understanding that the present disclosure is to be considered as an exemplification of the principles of the invention and is not intended to limit the invention to the embodiment illustrated. The scope of the invention will be pointed out in the appended claims.

A single window construction embodying the invention is illustrated in Fig. 1 wherein the window is mounted in a building wall, indicated generally at 1, and comprises a head 2 and window sill 3 which are connected by vertically extending spaced apart side jambs one of which is indicated at 4 in Figs. 3 and 4. Upper and lower window sash 5 and 6, respectively, are slidably mounted in the window frame.

The single window construction is shown in greater detail in Figs. 2, 3, and 4. The jamb 4 has a spring type weatherstripping member 7 in which the window sashes 5 and 6 are slidably mounted and the jamb is mounted in a wall construction which, as shown, may be composed of studs, one of which is indicated at 8. Rock lath 9 and plaster 10 form the inner side of the wall. Sheathing 11 and siding 12 form the outer weather side of the building wall.

As illustrated in Fig. 4, the window sill 3 has a window underlying inner sill or section 13 which at its end 13a fits into a groove provided in the lower end of side jamb 4, and a outer sill section 14 of the window sill 3 is formed integral with the section 13. The outer section 14 is longer than section 13 and is of a length sufficient to terminate flush with the back of the side jamb 4 to provide a base upon which a blind stop 15 may be seated.

A brick mold 16 overlaps the blind stop 15 and the sheathing 11 and extends between the head 2 and window sill 3. The lower end of the brick mold 16 is stepped so that a part 17 rests on the outer section 14 of the window sill and another part 18 extends down and laps the end or extension of the window sill section 14 to enclose the end thereof and extend the window sill section out to full length. The part 18 of the brick mold has a groove 19 on its underside which continues the drip groove machined on the underside of the window sill section 14.

An important feature of my invention is that the window sill 3 may be preformed and treated and is optionally usable without cutting either in a single window construction, as described above, or may be used in multiples

to form the window sill of a multiple window unit, this being illustrated in Figs. 5 and 6.

As shown in Figs. 5 and 6, a pair of adjacent side jambs 20 and 21 are placed in back to back contact and are grooved to receive the ends 24 and 25 of window underlying inner sill sections 22 and 23 of window sills indicated generally at 26 and 27, respectively. The outer sill sections 28 and 29 of the window sills 26 and 27 respectively abut each other at their ends as indicated at 30 to form a continuous window sill and a mullion composed of a blind stop 31 and a casing 32 may extend upwardly from the outer sections 28 and 29 of the window sill to complete the window construction.

The use of the new window sill construction avoids cutting on the job which heretofore has been required to cut the usual "sill lugs" which leaves a window sill with rough cut ends and removes the end grain portion of the window sill member which has usually been previously treated with a toxic preservative.

I claim:

1. A window frame construction comprising, spaced apart side jambs forming the sides of the frame, a window sill forming the bottom of the frame and having a window underlying inner sill extending between the jambs, an outer sill integral with said inner sill positioned in front of the jambs and of a length to have transverse end faces terminate flush with the back of the jambs, a blind stop extending vertically in front of each jamb and having its lower end seated on an end of said outer sill, and a brick mold extending vertically in front of each blind stop and having a stepped lower end so that

a part thereof rests on an end of the outer sill and another part abuts the transverse end face of the outer sill end and fills the sill out to full width.

2. A window frame construction comprising, spaced apart side jambs forming the sides of the frame, a window sill forming the bottom of the frame and having an inner sill extending between the jambs and an integral outer sill on the outer weather side of the frame, said outer sill having ends positioned outwardly of the jambs and having end faces extending transversely to the length thereof terminating flush with the back of the jambs, a blind stop extending upwardly from each end of the outer sill and in engagement with the adjacent side jamb, a brick mold extending upwardly from each end of the outer sill and of a width to partially lap the blind stop and extend beyond the end of the outer sill against which building siding or the like may abut, and means defining a lower end on each brick mold terminating at two levels with the part thereof lapping the blind stop at a first level resting on the outer sill end and the remainder of the brick mold end at a lower lever abutting the outer sill transverse end faces.
